UNITED STATES PATENT OFFICE

2,445,190

ELECTRIC CIRCUIT BREAKER

Benjamin E. Spiro, Philadelphia, and Ralph J. Baskerville, Merwood Park, Pa., assignors to General Electric Company, a corporation of New York

Application December 20, 1944, Serial No. 568,983

3 Claims. (Cl. 200—144)

1

Our invention relates to electric circuit breakers and more particularly to electric air circuit breakers of the type disclosed and claimed in Linde Patent 2,293,513, granted August 18, 1942, and assigned to the same assignee as the present application. Specifically, our invention is an improvement on a circuit breaker of the type disclosed in Linde Patent 2,335,068, granted November 23, 1943, and also assigned to the same assignee as the present application.

Air circuit breakers of the type disclosed in the above-mentioned Linde patents have been used very extensively within the past several years. These circuit breakers employ an arc chute of inorganic material, which arc chute is closely adjacent the contacts of the circuit breaker between which the arc is drawn. Our invention is particularly concerned with the construction of the arc chute and supporting means therefor which are simple and compact and which permit ready accessibility to the contacts of the circuit breaker.

It is an object of our invention to provide an arc chute for an electric circuit breaker which is simple, compact, efficient in operation, and which is readily removable to permit inspection of the contacts of the associated circuit breaker.

It is another object of our invention to provide a new and improved arc chute including supporting means therefor for an electric circuit breaker.

Further objects and advantages of our invention will become apparent as the following description proceeds and the features of novelty which characterize our invention will be pointed out with particularity in the claims annexed to and forming a part of this specification.

For a better understanding of our invention, reference may be had to the accompanying drawings in which Fig. 1 is an elevational view of an electric circuit breaker embodying our invention with certain portions broken away; Fig. 2 is a sectional view of the arc chute only, taken on line 2—2 of Fig. 1; Fig. 3 is an exploded view of the arc chute of Fig. 1 to illustrate the construction of the arc chute, and Fig. 4 is a sectional view taken on line 4—4 of Fig. 3 assuming an assembled arc chute in Fig. 3.

Referring now to the drawings, there is illustrated an electric circuit breaker in some respects quite similar to the electric circuit breaker disclosed in the above-mentioned Linde Patent 2,335,068. The electric circuit breaker illustrated comprises a main supporting frame or unit 1 for the relatively movable contact structure which comprises relatively fixed current carrying con-

2

tacts 2 and arcing contacts 3 and cooperating movable current carrying contact 4 and movable arcing contact 5. Movable contacts 4 and 5 are supported on an arm 6 which is pivotally mounted at 7 to one end of a circuit breaker conductor stud 8. The relatively stationary contacts 2 and 3 are electrically connected to a conductor stud 9. Movable contacts 4 and 5 are operated by means of an operating rod 10 connected to arm 6 and also connected to an actuating mechanism mounted within the structure generally indicated at 11 in Fig. 1. The conductor studs 8 and 9 serve as plug type disconnect contacts for the circuit breaker unit and when they are connected to a live power circuit relative separation of the contacts will cause an arc to be drawn.

For the purpose of interrupting a power arc drawn between the contacts, an arc extinguishing structure or arc chute, generally indicated at 12 is provided to receive the arc. Generally such a circuit breaker comprises a plurality of arc chutes, one for each phase conductor of the power circuit to be controlled. It will be understood that our invention is equally applicable to a single phase or polyphase circuit breaker. As is illustrated in the drawings, the arc chute 12 is of the so-called "down draft" type such as is disclosed in Linde Patent 2,335,068, referred to above. By down draft type is meant that the arc gases from the arc chute are discharged downwardly. It should be understood, however, that our invention is also applicable to circuit breakers which are not of the down draft type, such, for example, as circuit breakers, wherein the gases from the arc chutes are discharged laterally as in Linde Patent 2,293,513.

The arc chute 12 of our circuit breaker is preferably constructed in accordance with the arc shield disclosed and claimed in Boehne Patent 2,270,723, granted January 20, 1942, and assigned to the same assignee as the present application. Preferably, the arc extinguishing structure or arc chute 12 comprises spaced side walls 13 and 14 composed of arc resisting material such as an asbestos cement compound, each side wall having on the side facing the other wall a plurality of parallel fins, ridges or barriers 15, as best shown by Figs. 2 and 4. The fins 15 are preferably integral with the side walls 13 and 14, which side walls are preferably clamped together as by means of bolts 16 with the ridged or finned sides thereof adjacent to each other. The length and spacing of the fins or ridges 15 are such that when the side walls 13 and 14 are clamped together the fins are spaced and interleaved with

respect to each other, that is, in staggered relation so as to form a sinuous or zigzag passage 17 into which the arc is driven from the entrance portion 18 of arc chute 12 which is best shown in Fig. 4.

Referring more particularly to Fig. 4, there is illustrated a transverse section of the zigzag arc passage 17 defined by interleaving fins or ridges 15. The fins or ridges 15 are shown as tapering towards the entrance 18 of the arc chute 12. It will be observed that this tapered portion of the fins causes the arc passage 17 to be more and more restricted as the arc approaches the exhaust portion of the chute.

Preferably the chute sides 13 and 14 are molded with the ridges or fins 15 integrally formed therewith and any recesses, raised portions or the like are formed during the molding process. To save the expense of two separate molds, our chute sides 13 and 14 may be molded as identical pieces from a single mold. Fig. 3 shows how the chute sides 13 and 14 may be molded as identical pieces, the dotted portions 19 and 20 being initially included in the molded chute sides 13 and 14, respectively. The dotted portion 19 of chute side 13 is cut away and correspondingly the dotted portion 20 of chute side 14 is cut away so that the chute sides are defined by the solid lines of Fig. 3. The fins of the chutes are arranged so as to be unsymmetrical about a central arc dividing member 21 associated with each chute side whereupon interleaving of the ribs or fins 15 will result upon assembly of the chute sides initially molded identical in shape.

As initially molded and clearly evident from Fig. 3, each chute side 13 and 14 is provided with L-shaped recesses 22 and 23, with the base of the L-shaped recesses 22 and 23 pointing towards each other. Each chute side 13 and 14 is also provided with a pair of curved arcing horn recesses 24 and 25 which are of similar shape, recess 24 being inverted relative to recess 25. By cutting away portion 19 of chute side 13, indicated in dotted lines in Fig. 3, a portion of each of the recesses 22 and 24 is cut away. By cutting away portion 20 of chute side 14, indicated in dotted lines in Fig. 3, a portion of each of the recesses 23 and 25 is cut away.

The lower end of arc chute 12 is the exhaust end of the arc chute. In order to cool the arc gases properly before being exhausted from the chute a plurality of parallel arranged cooling plates 26 are provided. These cooling plates 26 are very similar to the cooling plates provided in the above-mentioned Linde patents for cooling the arc gases and are preferably formed of copper or other good thermal conducting material. These cooling plates are inserted in notches 27 preferably molded in the chute sides 13 and 14.

The construction of the contacts of the circuit breaker form no part of our invention. Preferably, however, movable arcing contact 5 supported on pivotally mounted arm 4 moves through the entrance portion 18 of arc chute 12. As illustrated, movable arcing contact 5 moves closely adjacent to an arcing horn 29 supported in recesses 24 and 25 of chute sides 13 and 14, respectively, the edges of arcing horn 29 being disposed in the cooperating recesses 24 and 25. Arcing horn 29 is provided with an extension 30 which includes the opening 31 so that arcing horn 29 may be electrically connected, as by a bolt passing through opening 31 to one side of the associated electric circuit. An arcing horn 32 adapted to be associated with the other side of said associated

electric circuit is positioned in cooperating recesses 26 and 24 of chute sides 13 and 14, respectively. Arcing horn 32 is electrically connected to a blowout coil 33 mounted on a core 34 and separated from the coil by an insulating cylinder 35. The core 34 of the blowout coil 33 is adapted to extend through drilled openings such as 36 in the chute sides 13 and 14 so as to abut magnetic plates 37, one associated with each chute side 13 and 14. A suitable bolt 38 passing through the chute sides, plates 37 and an opening in core 34 holds the core 34 and magnetic plates 37 together so as to produce a strong magnetic field for moving the arc into arc chute 12. In order to prevent magnetic plates 37 from rotating about bolt 38, each of the chute sides 13 and 14 is provided with a raised portion 39 preferably integrally formed therewith during the molding process. Raised portion 39 cooperates with a notched-out portion 40 in the magnetic plates 37.

One end of magnetic blowout coil 33 is connected to arcing horn 32, as is indicated at 41. The other end of magnetic blowout coil 33, as is indicated at 42, is connected to a conducting supporting member 43 which is a bar-like piece bent across its width into a generally U-shaped configuration the lower portion of which matches the cooperating recesses 23 and 22 formed in chute sides 13 and 14, respectively. When the chute sides 13 and 14 are bolted together, as indicated in Figs. 2 and 4, the lower portion which includes leg 44 of the U-shaped member 43 is held with its edges effectively keyed into the L-shaped recesses 23 and 22 in chute sides 13 and 14, respectively. Accordingly the arc chute 10 may be supported firmly and reliably from the upper leg of the U-shaped member 43 for it will be apparent that the support 43 cannot be displaced from its keyed position in the assembled arc chute until the two sides are unbolted and separated from one another.

It will be discerned that the arc chute supporting member 43 derives its tenacity with respect to the arc chute from the fact that the main body portion of the member is provided with an effective anchorage afforded by the projecting or offset portion 44 and the corresponding grooves or recesses provided in the chute sides for snugly receiving therein the edges of the main body and offset portions of the supporting member.

Preferably, conducting supporting member 43 is fastened by means of a single cap screw 45 to an extension 46 of the stationary contact structure which is electrically connected to the bottom of conductor stud 8.

In order to support the other side of the arc chute 12, we provide a fabricated supporting member 47 comprising two vertically extending pieces 48 identical in configuration, joined together at the top by a U-shaped crossover member 49. The lower ends of the vertical members 48 making up fabricated supporting member 47 are provided with an open ended disengaging slot 50. A single cap screw 51 passing through the bight of U-shaped member 49 of supporting member 47 holds the fabricated support 47 to the contact block supported from conductor stud 8. The open ended disengaging slots 50 are adapted to cooperate with a bolt 52 passing through arc chute 12 and through the opening 31 in arcing horn 29. It will be obvious that with the above construction the arc chute 12 can readily be removed merely by removing the cap screw 45 and loosening the bolt 52 after which the arc chute 12 may be slid to the left, as viewed in

Fig. 1, whereby bolt 52 becomes freed from the disengaging slots 58.

From the above discussion, it will be obvious that the cooperating recesses 23 and 22 of chute sides 13 and 14, respectively, provide a very simple means for securely affixing the arc chute supporting member 43 into the chute structure without the requirement of any additional fastening means whatsoever and furthermore with this construction a very easily removable arc chute is obtained. Moreover, it will be observed that during the interrupting operation, that is, after the movable contacts 4 and 5 have separated from the coating stationary contacts 2 and 3 respectively, the upper portion of supporting member 43 further cooperates in that it serves as a shunt path around the fixed contacts through which current flows for energizing the blowout coil coincidental with the transfer of the arc root from the fixed arcing contact 3 to the arc runner 32.

While we have shown and described a particular embodiment of our invention, it will be obvious to those skilled in the art that various changes and modifications may be made without departing from our invention in its broader aspects and we, therefore, aim in the appended claims to cover all such changes and modifications as fall within the true spirit and scope of our invention.

What we claim as new and desire to secure by Letters Patent of the United States is:

1. In an electric circuit breaker, supporting structure, an arc chute constructed of complementary parts, grooves in adjacent surfaces of said complementary parts, said grooves having one portion thereof angularly disposed with respect to another portion thereof, a supporting member having a portion thereof adapted to project outwardly from said arc chute and another portion thereof having an offset portion and being adapted to fit within the grooves in the complementary parts of said arc chute, whereby said supporting member is secured in position with respect to said arc chute, and means cooperating with the portion of said supporting member which projects outwardly from said arc chute for securing said supporting member to said supporting structure.

2. In an electric circuit breaker, supporting

structure, an arc chute constructed of complementary parts, grooves in adjacent surfaces of said complementary parts, said grooves having one portion thereof angularly disposed with respect to another portion thereof, a supporting member having a portion thereof adapted to project outwardly from said arc chute and another portion thereof having an offset portion and being adapted to fit within the grooves in the complementary parts of said arc chute, whereby said supporting member is secured in position with respect to said arc chute, means cooperating with the portion of said supporting member which projects outwardly from said arc chute for securing said supporting member to said supporting structure, a supporting arm secured to said supporting structure, and means for securing said arc chute to said supporting arm.

3. In an electric circuit breaker, supporting structure, an arc chute, a supporting member secured to said arc chute and having an outwardly projecting portion, means for removably securing the outwardly projecting portion of said supporting member to said supporting structure, a supporting arm secured at one end thereof to said supporting structure, a slot in the other end of said arm, and means on said arc chute for removably connecting said arc chute to said supporting arm by a sliding engagement with said slot.

BENJAMIN E. SPIRO.
RALPH J. BASKERVILLE.
